UNITED STATES PATENT OFFICE

167,179

LAMP

James W. Stewart, Denver, Colo.

Application February 11, 1952, Serial No. 18,458

Term of patent 14 years

(Cl. D48—20)

To all whom it may concern:

Be it known that I, James W. Stewart, a citizen of the United States, residing at Denver, in the county of Denver and State of Colorado, have invented a new, original, and ornamental Design for a Lamp, of which the following is a specification, reference being had to the accompanying drawing, forming part thereof.

The single drawing figure is a perspective view of a lamp showing my new design, the opposite sides being similar.

I claim:

The ornamental design for a lamp, as shown and described.

JAMES W. STEWART.
